UNITED STATES PATENT OFFICE.

GEORGE S. BACKUS, OF LEADVILLE, COLORADO, ASSIGNOR TO FREDERICK W. BRAUN,
OF LOS ANGELES, CALIFORNIA.

SAMPLER.

1,238,058.

Specification of Letters Patent. Patented Aug. 21, 1917.

Application filed September 23, 1914. Serial No. 863,206.

To all whom it may concern:

Be it known that I, GEORGE S. BACKUS, of Leadville, Lake county, State of Colorado, have invented certain new and useful Improvements in Samplers, of which the following is a specification.

The invention relates to devices for sampling pulverized ores, grain, drugs and other similar materials.

10 An object of the invention is to provide a sampler which is continuous in operation.

In the majority of samplers as heretofore constructed, a portion, usually the larger portion, of the material being sampled is retained in the apparatus so that only a comparatively small amount of material could be sampled at one operation, after which the apparatus must be opened and the collected material removed, before another 20 sample could be run through or before more of the same material could be run through. In samplers, the material is usually quartered, three quarters of the material being retained and the other quarter discharged, 25 and the discharged quarter constitutes the sample.

In the sampler of the present invention, the material is separated into two portions, usually in the ratio of three quarters and 30 one quarter, and both portions are discharged separately from the apparatus into suitable collection receptacles, and since both portions are continuously discharged, a sample of any size or volume may be obtained.

35 The invention possesses other advantageous features, some of which, with the foregoing, will be set forth at length in the following description, where I shall outline in full that form of the invention which I have 40 selected for illustration in the drawings accompanying and forming part of the present specification. In the drawings I have shown only one specific form of my generic invention, but it is to be understood that I 45 do not limit myself to such form because my invention may be embodied in a multiplicity of forms, each being a species of my said invention. It is also to be understood that by the claims succeeding the description of my invention I desire to cover 50 the invention in whatever form it may be embodied.

In said drawings:

Figure 1 is a side elevation of the apparatus, parts thereof being shown in section 55 to illustrate the interior arrangement.

Fig. 2 is a top or plan view of the upper dividing bucket.

Fig. 3 is a section of the upper bucket taken on the line 3—3 Fig. 2. 60

Fig. 4 is a top or plan view of the lower dividing bucket.

Fig. 5 is a section of the lower dividing bucket, taken on the line 5—5 Fig. 4.

Fig. 6 is a top or plan view of the structure arranged between the upper and lower buckets. 65

Fig. 7 is a section of the intervening structure taken on the line 7—7 Fig. 6.

The apparatus comprises a suitable frame 70 or support 2 in which are arranged bearings for the drive shaft 3, which shaft may be rotated by any suitable means. Pivottally attached to the upper end of the frame 2 is a hopper 4, provided with a discharge chute 75 5, the opening of which is controlled by the adjustable gate 6. The bottom of the hopper is inclined toward the discharge chute, and means are provided for rocking or jolting the hopper to insure the discharge of the 80 material therefrom. Pivoted to the hopper is a rod 7 on the lower end of which is a roller 8 which contacts with an irregular surfaced cam 9 fixed to the drive shaft. The roller 8 is held in engagement with the cam 85 by a spring 12 attached at one end to the hopper and at the other end to the frame 2. As the drive shaft rotates, therefore, the hopper is subjected to continuous jolting which causes the material therein to flow 90 through the discharge chute.

Secured to the frame 2 is a bracket or structure 13 which is arranged in line with the drive shaft, and which is provided with a hollow hub 14 through which the drive 95 shaft extends. The bracket is provided with three concentric walls 15—16—17 spaced from each other, and forming therebetween annular passages for the material passing through the apparatus, as will be herein- 100 after explained.

Arranged on the bracket is a casing formed of the upper casing 18 and the lower casing 19, and the lower casing having an

inclined bottom terminating in a discharge chute 22. The casings are preferably attached to the outer circular wall 17, so that they inclose the entire dividing apparatus.

5 Arranged within the upper casing 18 is a dividing element or bucket 23 which is arranged to be rotated and arranged within the lower casing 19 is a similar element or bucket 24 arranged to be rotated in the opposite direction. I have termed these elements buckets, since that is the usual commercial name for the dividing elements, and the term is to be construed as meaning a dividing means and not as a bucket in the 15 ordinary sense of the word.

At the center of the bracket 13 there is formed a vertically disposed bearing 25 in which is arranged a shaft or axle 26. Rotatably mounted on the shaft 26, above and 20 below the bearing 25, are bevel gears 27—28 which are enmeshed with the bevel gear 29 secured to the end of the drive shaft. When the drive shaft is rotated, the gears 27 and 28 rotate in opposite directions. The gears 25 are arranged within the inclosure of the wall 15, which is higher than the other walls, and which wall serves in part to prevent the material passing through the apparatus from coming into contact with the gears.

30 Secured to the upper gear 27 is the upper dividing element or bucket 23 and secured to the lower gear 28 is the lower dividing element or bucket 24, and when the apparatus is in operation, the buckets rotate in 35 opposite directions.

The upper dividing element 23 comprises a conical plate 64 of substantially the same diameter as the ring 16. Formed on the plate are a plurality of radial walls or ribs 46 31—32—33—34, which divide the surface of the plate into a plurality of sectors 35—36—37—38. The walls are substantially triangular in shape, and their upper edges are substantially horizontal or may slope upwardly 45 slightly toward their outer ends. The diametrically opposite sectors 35 and 37 are closed at their periphery by the segmental walls 41 and 42, which walls are substantially vertical and are joined to the walls 31—32 and 33—34 respectively, forming triangular shaped pockets. In the bottom wall of the pockets are arc-shaped apertures 43—44 which are concentric with the conical bottom and which are spaced radially from the outer 50 edge thereof. Any material fed into pockets 35 and 37 discharges through the apertures 43 and 44 and any material which is fed onto the bottom in the sectors 36 and 38 discharges over the periphery of the bottom 55 wall. With the dividing element rotating, a stream of material fed thereto is divided into two substantially equal portions, one portion discharging through the apertures 43 and 44 and the other portion discharging 60 over the edge of the bottom. The portion 65

which discharges through the apertures passes downwardly through the annular passage between the walls 15 and 16 of the bracket, and the portion which discharges over the edge discharges into the casing 18, 70 passes downward between the walls 16 and 17 of the bracket into the casing 19, whence it discharges through the spout 22.

The casing 18 is provided with a cover 45 in which, at one side of the center, is arranged a chute 46 into which the material being sampled is fed from the hopper. This chute is preferably arranged so that it discharges the material at one side of the center of the upper dividing element 23 so that the 80 material is not fed to two diametrically opposite sectors at the same time.

The lower dividing element 24 is divided into a plurality of annular sections by the radially disposed walls 51—52—53—54, 85 which extend outward from the inner circular wall 55, which is of substantially the same diameter as the wall 15 on the bracket. The walls 51—52 and 53—54 are joined by circular walls 56—57 forming two pockets 90 58—59. The walls 56 and 57 slope inwardly and downwardly, the diameter of the wall at its upper edge being substantially the same as the diameter of the wall 16 on the bracket. The pockets 58 and 59 are open at the bottom and discharge the material entering them into the conical chute 61 which extends through the bottom of the casing 19, the diameter of the lower edges of walls 56 and 57 being substantially the same as the 100 diameter of the upper edge of chute 61. Between the walls 52—53 and 54—51 are formed outwardly inclined walls 62—63 which slope from the upper edge of wall 55, the diameter of the lower edges of walls 62—63 being slightly greater than the diameter of the upper edge of the chute 61. 105

The material passing downwardly through the annular passage between walls 15 and 16, engages the dividing element 24 and one-half of it is diverted into the chute 61 and one-half is discharged into the casing 19, whence it discharges through the spout 22. It is evident, therefore, that substantially one-fourth of the material fed into the chute 110 46 discharges through the chute 61 and substantially three-fourths of the material discharges through the spout 22. In passing through the apparatus the material is thoroughly mixed and divided and the portion discharged through the chute 61 is a representative sample. Since none of the material is retained in the apparatus, there is no limitation as to the volume of material which may be passed through the apparatus at one 115 operation, because the apparatus may be operated continuously.

I claim:

1. In a dividing apparatus, a casing having two discharge apertures, a plurality of 120

dividing elements rotatable about a vertical axis arranged in said casing, a stationary element interposed between and supporting said dividing elements, said dividing elements being adapted to divide material and direct the divisions thereof to said apertures respectively, and means for rotating said dividing elements.

2. In a dividing apparatus, a casing having two discharge apertures, two dividing elements oppositely rotatable about a vertical axis arranged in said casing, a stationary element interposed between and supporting said dividing elements and means for rotating said dividing elements, whereby material is divided and subdivided and one portion of divided and one portion of subdivided material is directed to one aperture and the other subdivided portion is directed to the other aperture.

3. In a dividing apparatus, a casing having two discharge apertures, a stationary element in said casing, two oppositely rotatable conical plates in said casing divided into a plurality of sections and arranged one above and one below said stationary element and means on said stationary element for rotating said conical plates, whereby material is divided by the upper plate and one portion directed toward one discharge aperture and the other portion directed upon the lower plate, and the divided portion is subdivided by the lower plate and one subdivision thereof is directed toward the first mentioned aperture and the other subdivision toward the other aperture.

4. In a dividing apparatus, a rotatable conical plate divided into sections and adapted to divide material and discharge the divided portions, a stationary element supporting said dividing element and provided with a plurality of passages through which the divided portions respectively pass, an oppositely rotatable conical plate divided into sections arranged below and adapted to receive material from one of said passages and simultaneously subdivide and separately discharge the subdivided portions, and means for rotating said plates.

5. In a dividing apparatus, a casing having two discharge apertures, a stationary element arranged in said casing, a rotatable conical plate divided into sections arranged upon the upper side of said stationary element, and a second rotatable conical plate divided into sections arranged upon the lower side of said stationary element, said conical plates being adapted respectively to divide and subdivide material and to direct one divided and one subdivided portion

thereof to one aperture, the other subdivided portion of said material being directed to the other aperture.

6. In a dividing apparatus, a bracket having annular walls spaced apart, forming therebetween a plurality of passages, a rotatable dividing element arranged above the bracket adapted to divide material and direct the divided portions through said passages respectively, a rotatable subdividing element arranged below one of said passages and means for rotating and supporting said elements.

7. In a dividing apparatus, a bracket supported by the frame of the apparatus having annular walls spaced apart, forming therebetween a plurality of passages, a casing secured to the outer annular wall and having a discharge aperture, a rotatable dividing element therein adapted to divide material and direct the divided portions each through a different one of said passages, a rotatable subdividing element arranged below one of said passages, adapted to divide the material which passes through said passage, and a chute arranged below the subdividing element, extending through the casing and arranged to receive a subdivided portion of the divided material and means to rotate the dividing and the subdividing elements.

8. In a dividing apparatus, a bracket supported by the frame of the apparatus having annular walls spaced apart and forming therebetween a plurality of passages, a horizontal shaft and a vertical shaft mounted in said bracket, bevel gears rotatably mounted on opposite ends of the vertical shaft, a bevel gear on the horizontal shaft engaging said first named gears, a dividing element mounted on the upper gear on the vertical shaft adapted to divide material and discharge the divided portions separately through said passages, a subdividing element secured to the gear on the lower end of the vertical shaft and arranged below one of said passages, said subdividing element being adapted to subdivide one of the divided portions of material, a chute arranged below the subdividing element adapted to receive a subdivided portion of the material and means to rotate said horizontal shaft.

In testimony whereof, I have hereunto set my hand at Leadville, Colorado, this third day of Sept. 1914.

GEORGE S. BACKUS.
